[57] CLAIM

The ornamental design for a floor slat for hog confinement facilities or similar article, substantially as described and shown.

DESCRIPTION

FIG. 1 is a perspective view of the design showing the floor slat broken away along its length.

FIG. 2 is an enlarged partial top plan view of the design.

FIG. 3 is a partial side elevational view in the same scale as shown in FIG. 2.

FIG. 4 is an end view shown in the same scale as FIGS. 2 and 3.

FIG. 5 is a partial bottom plan view in the same scale as FIGS. 2-4.

The slat has the same cross-sectional configuration throughout its entire length.
